UNITED STATES PATENT OFFICE.

GEORGE W. KING, OF CLEVELAND, OHIO.

BRICK-MACHINE.

SPECIFICATION forming part of Letters Patent No. 443,321, dated December 23, 1890.

Application filed July 22, 1890. Serial No. 359,533. (No model.)

To all whom it may concern:

Be it known that I, GEORGE W. KING, of Cleveland, in the county of Cuyahoga and State of Ohio, have invented certain new and useful Improvements in Presses; and I do hereby declare the following to be a full, clear, and exact description of the invention, such as will enable others skilled in the art to which it pertains to make and use the same.

10 My invention relates to improvements in a press; and it consists in certain features of construction and in combination of parts hereinafter described, and pointed out in the claims.

15 In the accompanying drawings, Figure 1 is an end elevation, partly in section. Fig. 2 is a side elevation, partly in section. Fig. 3 is a plan of the table and attachments. Fig. 4 is a plan of the yoke that operates the fol- 20 lower. Fig. 5 is a plan of the rock-shaft and attachments. Figs. 6 and 7 are, respectively, plan and elevation of a crank-shaft, the same being a modification, hereinafter described.

The press shown in the drawings is adapted 25 to press rectangular bricks that have been molded or dried or partially dried; but the press, by changing, for instance, the form of the die or cup and plunger, may be adapted to press various shaped tiles or other mate- 30 rial.

A represents the supporting-frame, that is preferably a cast-iron square or rectangular hollow column, cast open at top and bottom, the column being provided with suitable side 35 openings A' to give access to the internal mechanism. The column near the bottom has side pockets A², open top and bottom, for purposes hereinafter mentioned. The column at the rear has an opening A³ for accommo- 40 dating pitman F. This form of supporting-frame is not essential, but is compact, strong, and convenient, and hence is preferred.

B is a table fastened on top the column or other supporting-frame. The table at the 45 center thereof has a depending flange B', that extends down inside the column or frame, this flange inclosing a chamber B², that serves as a die, mold, or cup in which the brick, tile, or other material is pressed, and hence this 50 chamber and the plunger that operates therein may be rectangular, as shown, or may be square or round, or of any other form, accord-

ing to circumstances. We will suppose, however, that chamber B² is rectangular, as shown, and is adapted to receive an ordinary 55 unburnt brick.

C is a reciprocating plunger adapted to fit the die or cup, this plunger constituting a part of and preferably being integral with cross-head C'.

D is the bottom member of the die, cup, or mold, and may be cast integral with flange B', or may be cast separate and then bolted to the under side of this flange, as shown, according to circumstances. If this die is round, 65 so that it can be bored, or if the die is to be lined with steel plates backed by soft metal, as is frequently done in such cases, member D could be cast integral with flange B'. In other cases member D had better be cast separate for convenience in dressing the die, cap-screw d² being shown for securing this member to flange B'.

E E' are toggle-arms. The upper arm E has a rounded upper end that fits in a corresponding groove in the bottom of member D. This toggle-arm has also trunnions e, and member D is provided with caps or half-boxes d d for engaging the lower side of these trunnions to hold the toggles suspended, with the upper 75 toggle-arm always in contact with member D. Caps d are secured to member D by suitable cap-screws d'. The lower toggle-arm E' has large strong trunnions e', one of which is shown more clearly at the left hand in Fig. 1. 80 The two toggle-arms are pivotally connected by a strong bolt or pin e². This pin or bolt also passes loosely through a hole in the forward end of pitman F.

G G are the side bars that connect the lower 90 toggle-arm with the cross-head. These side bars have rectangular heads G', pierced laterally for receiving with an easy fit trunnions e', these heads fitting loosely in pockets A² aforesaid. Above the heads the side bars are 95 preferably round rods, the upper sections thereof being screw-threaded and provided with nuts g above the cross-head, and provided with jam-nuts g', engaging the under side of the cross-head, the latter having suitable holes cored therein for receiving the screw-threaded sections of these side bars. With such construction the cross-head may 100 be adjusted vertically by manipulating these

nuts, after which by tightening the nuts the cross-head is rigidly secured to the side bars. To save dressing the inside of pockets A² the latter are constructed considerably larger internally than heads G', and gibbs are provided, and adjusting-screws a', as shown more clearly in Fig. 2, these gibbs being simply flat plates of metal with holes drilled therein to receive the reduced ends of the set-screws. Near the upper end of the column are boxes a², through which the side arms respectively reciprocate.

II is a rock-shaft journaled in boxes a², this rock-shaft having a socket II' for inserting a hand-lever II², the latter being usually of wood. Shaft II has rock-arms h h', provided with a removable wrist-pin h', the latter having an easy fit in a lateral hole at the rearward end of pitman F.

I is a follower consisting of a metal plate nicely fitting inside of the die, this follower being connected by rods I' with yoke i, rods I' passing loosely through holes in member D. Yoke i has forked ends i', (shown more clearly in Fig. 4,) the prongs whereof pass astride bars G. The latter are provided with adjustable collars g² secured to the side bars preferably by set-screws. (Shown at g³.) With the upstroke of the side bars, collars g² engage the under side of the yoke, whereby the yoke and follower I are elevated to lift the brick or other material from the die, and by means of stop K engaging the opposing end of member H' and by means of adjusting-collars g² the follower is lifted to a position flush with the top surface of the table. An adjustable stop K' is provided, this stop being adapted to engage the hand-lever, when on the downstroke of the latter the toggle-arms are brought in line. With the hand-lever in the position shown in dotted lines, Fig. 2, the toggle-arms are deflected, as shown, whereby the plunger is elevated the necessary distance above the table to admit of removing the bricks or other material.

L is a plate of metal adapted to slide on the table, the latter having upwardly-projecting ribs b that embrace and serve as guides for plate L. To the table are secured stops b' b² that limit the end movement of plate L. Plate L is provided with openings L' L², located, say, an inch or two apart, and each opening corresponds in plan with the chamber of the die. Plate L is provided with handles l l for sliding the plate endwise, the relation of parts being such that when plate L engages stop b' opening L' is directly over the die, and with the plate engaging stop b² opening L² is over and registers with the die.

In the position shown in Fig. 3 a brick is supposed to be in the die being pressed. Meantime the brick that has already been pressed is supposed to be removed from opening L² and another brick substituted. On the next upstroke of the plunger the brick in the die is raised by the follower to a position flush with the table, and plate L is then moved toward the left hand until it engages

stop b², by which movement the pressed brick is slid along the table toward the left hand from under the plunger, and the brick in opening L² is by the same operation brought to a position over the die. With the next stroke of the machine plate L is reversed to the place of beginning, and so on, the bricks being changed while the machine is operating upon the brick in the die. The one workman operates the hand-lever and the other workman removes and supplies the bricks. If it is desired to operate the press by power, a pitman can be attached to the hand-lever or crank M, and pitman m may be substituted in place of the rock-shaft and pitman F, (shown,) and a driving pitman or pulley may be mounted on the overhanging ends of such crank-shaft.

What I claim is—

1. In a press, the combination, with a stationary die or mold and a reciprocating plunger adapted to operate in connection with said die or mold, of a suspended toggle adapted to pivotally bear against the bottom member of the stationary die or mold, the other extreme of the toggle being operatively connected with the plunger for operating the latter, substantially as set forth.

2. In a press, the combination, with a stationary die or mold and a reciprocating plunger adapted to operate in connection therewith, of a suspended toggle adapted to pivotally bear against the bottom of such stationary die or mold, the other extreme of the toggle being pivoted to side bars that connect with the plunger mechanism, substantially as set forth.

3. In a press, the combination, with a stationary die or mold and a reciprocating plunger adapted to operate in connection with said die or mold, of a suspended toggle adapted to bear against the bottom member of the stationary die or mold, the other extreme of the toggle being operatively connected with the plunger, whereby the plunger is reciprocated by operating the toggles, the plunger having vertical adjustment on such connecting members, substantially as set forth.

4. In a press, the combination, with a supporting-frame, a stationary die or mold secured to the upper end thereof, and reciprocating plunger adapted to operate in connection with such die or mold, of a suspended toggle, the upper end thereof being adapted to pivotally bear against the bottom member of the stationary die or mold, and the other extreme of the toggle being pivoted to side bars, and the latter having screw-threaded sections engaging the cross-head of the plunger, with nuts mounted on the side bars and adapted to adjustably secure the cross-head in position, substantially as set forth.

5. In a press, in combination, a supporting column or frame bearing a stationary die or mold, a reciprocating plunger adapted to operate in connection with such die or mold, a suspended toggle adapted to bear against the

bottom member of the die or mold, the other end of the toggle being connected by side bars with the plunger, a rock-shaft and lever, rock-arms, and pitman, arranged, substantially as indicated, for operating the toggle, substantially as set forth.

6. In a press, in combination, a stationary die or mold, a reciprocating plunger adapted to operate in connection with such die or mold, a suspended toggle adapted to engage the die or mold, side bars connecting the toggle with the plunger, a follower adapted to operate in connection with said die or mold, a yoke operatively connected with such follower, such yoke being adapted to engage projecting members of the side bars, whereby the yoke and follower are lifted with the upstroke of the plunger, substantially as set forth.

20 7. In a press, in combination, a supporting-column bearing a stationary die or mold, a plunger, a toggle suspended from the under side of said stationary mold or die, and side bars connecting the toggle with the plunger, substantially as indicated, the column having external upright side pockets, and the side bars having heads adapted to reciprocate in such pockets, substantially as set forth.

30 8. In a press, the combination, with a table and a die or mold flush with such table, a plunger and a follower adapted to operate in connection with said die or mold, a suspended

toggle for operating the same, arranged substantially as indicated, of a slide adapted to reciprocate on such table, such slide having 35 openings corresponding with the opening of the die or mold, stops adapted on opposite sides of the die or mold to limit the movement of the slide to positions with one or the other of the openings of the slide registering, 40 with the die or mold, substantially as set forth.

9. In a press, the combination, with a stationary mold and a reciprocating plunger, of a sliding plate having two openings therein 45 adapted to alternately register with the mold and plunger, the said plate adapted to carry a brick to the mold and plunger for pressing, and at the same time carry away a brick that has been pressed, substantially as set forth. 50

10. In a press, the combination, with a stationary mold, a plunger and follower located within the mold for elevating the pressed article, of a sliding plate having two openings therein adapted to alternately register 55 with the mold, substantially as set forth.

In testimony whereof I sign this specification, in the presence of two witnesses, this 11th day of June, 1890.

GEORGE W. KING.
